Attorney

UNITED STATES PATENT OFFICE

JOSEPH H. MILLER, OF HOUSTON, TEXAS

DISPENSING CAN

Application filed July 17, 1931. Serial No. 551,382.

This invention relates to improvements in dispensing cans and is particularly directed to a can having a discharge-nozzle or spout through which the contents is discharged.

Cans of this general character are shown in prior U. S. Patents 1,570,270 of January 19th, 1926, and 1,638,778 of August 9th, 1927, both of which were granted to me.

The present improvement is more particularly directed to a valve structure whose operation, either to open or close, is materially facilitated by the mere act of turning the can to a pouring position or moving it in a reverse direction to stop the flow of fluid therefrom.

Cans of this type are especially useful for dispensing belt-dressing over driving-belts of machinery, which dressing should be protected against dirt or dust and should be kept sufficiently tight to prevent evaporation of some of its important ingredients. To this end, I provide an improved valve structure with means which will enable the flow of the contents to assist in opening as well as closing the valve structure.

With these objects in view, the accompanying drawing illustrates the invention, wherein,

Fig. 1 shows a can to which my improved device is attached.

Fig. 2 illustrates a cross-sectional detail through the nozzle,—the section being taken on the line 2—2 of Fig. 1.

Fig. 3 shows a portion of the can in side elevation and the nozzle in longitudinal section to illustrate the valve stem and parts therein,—the whole being tilted to pouring position.

Fig. 4 illustrates another cross-sectional detail through the nozzle, the section being taken on the line 4—4 of Fig. 3, and

Fig. 5 shows the nozzle with its wall broken away to illustrate in perspective the positions of the several parts when they are in the normal position with the valve closed.

Referring to the drawing, the numeral 10 designates the cylindric can-body having a head-end 11 with a breast 12 and a central nipple 13. The nipple is exteriorly threaded at 14 and has a central opening 15.

A flat ledge 16 is formed on the nipple about the opening 15 for a purpose that will presently be explained.

Obviously, the can may be filled through the opening 15.

The can is provided with a spout or nozzle 17 which is slightly tapered, being larger at its base or attaching-end than at its discharge-end, and at the larger end this nozzle is internally threaded so as to be detachably engaged with the nipple 13.

A partition 18 extends crosswise on the interior of the nozzle near its attaching-end and this partition has a central opening 20 while the metal around said opening forms an annular seat 19 which will overlie the flat ledge 16 of the nipple. A gasket 21 is placed between the seat 19 and the flat ledge 16 whereby to form a liquid-tight joint between the nozzle and nipple.

So far described, the structure of the present device is substantially the same as that of my prior patents hereinbefore referred to.

The outer or smaller end of the nozzle 17 has a permanently-attached cap 22 which latter may be soldered or otherwise attached to said nozzle-end. This cap has a central discharge-port 23 of a diameter that will permit the passage of fluid therefrom as well as allow a valve-stem 24 to freely extend therethrough.

The valve-stem 24 carries a disk-valve 25 and also has a finger loop 26 at the outer end beyond said valve.

The valve-stem passes freely through the port 23 of the cap and extends centrally and longitudinally of the nozzle.

The inner end of this stem is formed into a stop loop 27 which is of a diameter that is slightly smaller than the interior diameter of the nozzle at that point where the loop is situated when the stem is in the nozzle to its full limit, and the disk-valve 25 is seated on the cap 22 over the central port 23. In other words, the diameter of the stop loop 27 is such that it will normally be free from the interior tapered wall of the nozzle and will not engage that nozzle-wall until the stem has moved out sufficiently to move the disk-valve clear of the port and allow ample space,

such as that shown at 28 in Fig. 3, for the outpouring of the fluid.

On, and carried by the stem 24, immediately next to the stop-loop 27 is a cross-plate 29, which in the present structure is so combined with the nozzle and stem as to form a piston-like head in function. This plate 29 has two opposite sides cut away at 30 so as to leave gaps 31 between those sides and the interior 10 side wall of the tapered nozzle, while the diametrically-opposite sides 32 of said plate are curved, but, when the stem 24 is in its innermost position with the valve 25 seated, these sides 32 of said plate will be slightly 15 spaced from said nozzle wall,—the spaces 33 being indicated in the cross-sectional detail of Fig. 2.

This plate 29 serves a function in the present structure which is not performed in my 20 prior patents in which a plate of similar structure is shown, because in the patented structures the plates served as stops to limit the outward movement of the stem when the cap and stem were drawn out. In this instance, 25 the stem carries no cap but a valve,—the cap being held in place on the nozzle, and the stem passes freely through the cap.

In the present structure, the stop-loop 27 limits the outward movement of the stem 30 while the plate 29 acts as a movable partition or piston in that, when the can is tilted to pour liquid therefrom, the weight of the liquid against the underside of the plate pushes the plate and stem forward and automatically 35 unseats the valve 25. Upon reversal of the can from an inclined to an upright position, the trapped fluid in the nozzle against the forward side of the plate, plus gravity, will move the valve stem inwardly 40 and seat the valve over the port 23 thus automatically closing the latter.

The loop 27 therefore engages the tapered interior nozzle wall and stops forward movement of the valve-stem 24 before plate 29 can 45 become wedged in the tapered nozzle.

For these reasons, the plate 29 in this structure has a different function from the plates in my said prior patents.

The operation of the valve is thus an automatic one and does not depend upon the user 50 to think to close the can after each operation of dispensing.

It will be noted that the valve stem hangs pendants in the nozzle from the valve and 55 that no guide means to cause friction are provided on the nozzle,—all guide means being on and moving with the stem.

Preferably the stop loop 27 has a right-angle position relative to the cut-away sides 60 30 of the plate 29 and this loop together with the curved sides 32 of the plate prevent the stem from canting sufficiently to interfere with the operation of the valve.

Having described my invention, I claim,—
65 1. In a dispensing can the combination

with a can-body, of a tapered nozzle projecting from the can and having a discharge-port at the smaller end thereof, a stem extending freely through said nozzle-port and having a valve-plate which seats over said port and pendants sustain the stem in the nozzle and means on the stem within the nozzle against which fluid in the can may impinge to move the stem and unseat the valve.

2. In a dispensing can the combination with 75 a can-body, of a tapered nozzle projecting from the can and having a discharge-port at the smaller end thereof, a stem extending freely through said nozzle-port and having a valve-plate which seats over said port and 80 pendants sustain the stem in the nozzle, means in the nozzle to limit the outward movement of the stem when unseating the valve and means carried by the stem against which 85 the pressure of the material in the can may impinge to move the stem and unseat the valve.

3. In a dispensing can the combination with 90 a can-body, of a tapered nozzle detachably connected with and projecting from the can said nozzle having a discharge-port at its smaller end, a valve-plate seated over the outer side of the discharge-port, a stem depending from the valve plate into the nozzle and a loop formed on the stem and located 95 in the nozzle for engaging the wall of the latter to limit the outward movement of the stem when unseating the valve.

4. In a dispensing can the combination with 100 a can-body, of a tapered nozzle detachably connected with and projecting from the can said nozzle having a discharge-port at its smaller end, a valve-plate seated over the outer side of the discharge-port, a stem depending from the valve plate into the nozzle, a cross-plate attached to the stem against which fluid from the can may impinge to push the stem outwardly and unseat the valve and means carried by the stem to limit the outward movement of the stem and prevent the 110 cross-plate from wedging in the nozzle.

5. In a dispensing can the combination with 115 a can-body, of a tapered nozzle detachably connected with and projecting from the can, a cap secured to the smaller end of the nozzle and having a port therein, a stem passing freely through the cap-port into the nozzle, a disk-valve carried by the stem and seated on the cap at the outer side of the port and pendants supporting the stem in the nozzle, means on the pendant stem against which fluid from the can may impinge to move the stem and unseat the valve and means to limit the outward movement of the stem and valve.

In testimony whereof I affix my signature.

JOSEPH H. MILLER.
